CLAIM

The ornamental design of a jacket-stripping tool, as shown and described.

DESCRIPTION

FIG. 1 is a perspective view of the top, front, and right side for a jacket-stripping tool showing an embodiment of the new design;

FIG. 2 is a top view thereof;

FIG. 3 is a bottom view thereof;

FIG. 4 is a left view thereof;

FIG. 5 is a right view thereof;

FIG. 6 is a front view thereof; and,

FIG. 7 is a back view thereof.

The broken lines depict portions of the jacket-stripping tool in which the design is embodied that are not considered part of the claimed design.
